BABY CARRIAGE

Charles V. Kenney, Box 248, R.R. 2, Rockford, Ill.

Filed Aug. 10, 1960, Ser. No. 61,686

Term of patent 14 years

(Cl. D14—14)

I claim:

The ornamental design for a baby carriage substantially as shown and described.
